(57) **CLAIM**

The ornamental design for a combination athletic headband with removable cooling element, as shown and described.

DESCRIPTION

FIG. 1 is a perspective view of an athletic headband with removable cooling element in accordance with a first embodiment;

FIG. 2 is a perspective view of the athletic headband with cooling element of FIG. 1 illustrating a cooling element being inserted;

FIG. 3 is a front elevation view of the athletic headband with cooling element of FIG. 1;

FIG. 4 is a rear elevation view of the athletic headband with cooling element of FIG. 1;

FIG. 5 is a top plan view of the athletic headband with cooling element of FIG. 1;

FIG. 6 is a bottom plan view of the athletic headband with cooling element of FIG. 1;

FIG. 7 is a left side elevation view of the athletic headband with cooling element of FIG. 1, with a right side elevation view being a mirror image thereof;

FIG. 8 is a perspective view of an athletic headband with removable cooling element in accordance with a second embodiment;

FIG. 9 is a perspective view of the athletic headband with cooling element of FIG. 8 illustrating a cooling element being inserted;

FIG. 10 is a front elevation view of the athletic headband with cooling element of FIG. 8;

FIG. 11 is a rear elevation view of the athletic headband with cooling element of FIG. 8;

FIG. 12 is a top plan view of the athletic headband with cooling element of FIG. 8;

FIG. 13 is a bottom plan view of the athletic headband with cooling element of FIG. 8; and,

FIG. 14 is a left side elevation view of the athletic headband with cooling element of FIG. 8, with a right side elevation view being a mirror image thereof.

The partial human figure shown in broken lines in the drawings is provided to assist in illustrating how the claimed design appears when worn. The evenly-incremented broken lines that occur on the headband itself illustrate environmental structure. The line shown in long-short-short broken lines illustrates the bounds of the claimed design. None of the subject matter shown in broken lines in the drawings forms a part of the claimed design.
